UNITED STATES PATENT OFFICE.

JOHN MCTAMMANY, OF SPENCER, MASSACHUSETTS.

VOTING-MACHINE.

SPECIFICATION forming part of Letters Patent No. 546,076, dated September 10, 1895.

Application filed November 25, 1893. Serial No. 491,969. (No model.)

To all whom it may concern:

Be it known that I, JOHN MCTAMMANY, of Spencer, in the county of Worcester and State of Massachusetts, have invented certain new and useful Improvements in Voting-Machines, of which the following is a specification.

This invention relates more particularly to that class of voting-machines which employ mechanical counters; and one object of the invention is to reduce the size, weight, and number of parts in a voting-machine and to adapt the recording or registering mechanism for a regulation ballot or voting list.

15 A further object is increased efficiency in guarding against fraud by preventing repeating, preserving secrecy, and rendering the machine proof against ballot-box stuffing and manipulating.

20 A further object is to provide improved registering mechanism, whereby more speedy and accurate returns are obtained.

To the above ends the invention consists in the novel constructions and combinations of parts hereinafter described and claimed.

25 The accompanying drawings illustrate an embodiment of the invention.

Figure 1 shows a top plan view of the machine with the lid or cover removed, one of the 30 ballot-covering plates and ballot-sheets being omitted and its supporting-frame broken away to disclose the registering-wheels. Fig. 2 shows a longitudinal section of the inclosing box or casing with the registering mechanisms in elevation, with the exception of one, which appears in section. Fig. 3 shows a cross-section on line 3 3 of Fig. 1. Figs. 4 and 5 show details of parts of the registering mechanism. Fig. 6 shows a sectional view of an 40 implement designed for use by the voter.

The same letters of reference indicate the same parts in all the figures.

In the drawings, the letter *a* designates the outside inclosing box or casing, which is provided with a hinged lid or cover *a'*. A series of transversely-extending supports or frames *b* is suitably fastened within the box, and their flat top sides *b'* are formed with ridges *b*², extending from end to end, the object of 45 these ridges being to guide the voter to the actuating parts of the registering mechanisms, which parts appear alongside the ridges,

the ballot-sheets showing between the same. The transverse supports are formed below their top sides *b'* with grooves, which receive 55 transparent plates *c*, and said plates support ballot-sheets *d*, each being inscribed with groups of names of the different candidates for different offices. It will be observed that the plates and ballot-sheets are confined laterally by the supports *b*. The ballot-sheets are covered and thoroughly protected, while at the same time freely exposed to view, by means of transparent plates *e*, which fit between the transverse supports and are flush 60 with the top surfaces *b'* thereof. Said plates are confined at their ends between side bars of a rectangular frame, said side bars also extending over the ends of the transparent under plates *c*. (See Fig. 3.) Each side bar is 65 composed of two metal strips *e*² and a separating-block *e*¹, connected by rivets *e*³. The side bars are adjustably supported by screws *e*⁴, entered through lugs *e*⁵ on the interior of the box sides. The machine here shown is 70 designed to accommodate four ballot-sheets, which constitute a complete ticket of each party. Of course this number may be varied to suit the circumstances.

The registering mechanism for each ballot-sheet is of the same construction, and hence a description of one only will suffice. A series of gear-wheels *f*, having smooth peripheries *f*¹⁰, marked with graduated series of numbers, are mounted loosely on a shaft *f'*, within the box, 75 and are arranged in groups, according to the number of candidates for each office, the groups being separated by collars *f*². The numbers composing the groups may be varied to suit the circumstances. A push-piece *f*³ is 80 operatively connected with each registering-gear and extends through the top of the support *b* opposite the name of the particular candidate whose votes are to be registered by the wheel with which that push-piece connects. 95

The means of connection between each push-piece and a registering-gear are as follows: The push-piece is both longitudinally movable and rotatable in a bearing in the support *b* and is on the upper end of a spindle 100 *f*⁴, which is yieldingly supported by a spiral spring *f*⁵, surrounding its lower part and bearing at one end against a collar on the spindle and at the other against a part of the support

b. The upward movement of the spindle is limited by a collar f^6 upon it, abutting the support b . The push-piece is formed with a double spiral groove f^7 , (see Figs. 4 and 5,) and said groove is engaged by a pin f^8 , fixed in the support b . Normally the push-piece stands with the pin below the corner f^9 , formed by the meeting of the lower ends of the spiral grooves. Upon pressing down said push-piece the contact of one side of one spiral groove with the pin produces one-half of a complete revolution of the spindle by reason of the fact that said groove extends half-way around the push-piece. Upon the return of the spindle and push-piece the revolution is completed by the engagement of the other spiral groove with the pin.

To insure engagement of the pin throughout the complete circuit of the grooves, one of the grooves is extended beyond its intersection with the other, as shown at f^{12} , this construction being employed at the lower and the upper ends. The pin is normally in the lower extension, and the latter rounds into the intersecting groove, as at f^{13} , to insure clearance of the corner f^9 , the said intersecting groove receiving the pin. Under depression of the push-piece the latter is carried through somewhat more than a half-revolution, which carries the upper extension f^{12} into engagement with the pin and insures the engagement of the intersecting groove with the pin on the return of the push-piece and the continued turning of the push-piece in the proper direction to complete its revolution. A worm g is splined to the spindle f^4 , so that it turns therewith, but does not move longitudinally, and said worm meshes with the gear f . The worm rests upon a portion of the support b . It will now be seen that depression of the push-piece produces one complete revolution of the spindle. This complete revolution of the spindle moves the gear through one tooth and registers one vote on the periphery of the wheel. Means are provided for locking the spindle after one depression to prevent repeating, and with such means are combined means for simultaneously locking all the push-pieces of a group. Each spindle is formed with an annular shoulder g' , which will be termed a "driving-shoulder," for the reason that it acts against the carriage, hereinafter described, and drives the same to its locking position. The spindle is also formed with an annular groove g^2 , producing a shoulder, which will be called the "locking-shoulder," for the reason that locking means, hereinafter described, engage it, and thereby lock the spindle. A carriage h is supported in the frame b by a spring h' , surrounding a stem h^2 , fastened to said carriage, and the latter is adapted to move both longitudinally—i. e., up and down—and laterally and is confined laterally on the outer side by a flat spring h^3 . Sliding pins h^4 in said carriage project under the driving-shoulders of the spindles, and are held in that adjustment by springs h^5 . Upon de-

pressing any one of the spindles its driving-shoulder, by bearing on the pin of the carriage, impels the latter downward until its other pins reach the locking-shoulders of the other spindles and spring behind the same, and thereby lock these spindles. By this action the carriage is detained in its depressed position, so that upon the return of the depressed spindle which actuated it downward the locking-shoulder of that spindle is brought to engagement with a pin of the carriage and the spindle thereby locked. The design is to release the locking means by the operating device whereby access is gained to the ballot, and this may be effected in different ways. I prefer, however, to combine the locking means with the hinged lid a' in such a manner that the raising of the lid releases the lock and restores the parts to their normal condition. Therefore the regulations governing the use of the machine will demand that the cover be closed between each vote.

It will be observed that in the construction here shown a number of series of locking-carriages are arranged in line, and it is desirable to restore all parts of the machine to normal adjustment at once. To this end the following construction is employed: A rock-shaft i extends behind each series of carriages and at a point behind each carriage is provided with a cam i' , against which the carriage is held by the spring h^6 . Normally the carriage stands against a flat side of the cam and slides over the same in its up-and-down movement. One of the rock-shafts carries a drum i^2 , and a cord i^3 , attached thereto, is connected with the hinged lid a' . A voter having voted and the lid having been closed, upon raising the lid for the next voter the drum i^2 will be turned, and consequently the rock-shaft to which it is affixed, and the cam on said rock-shaft will push the carriages outward and withdraw their pins from engagement with the spindles, so that all the push-pieces are freed and the voter may depress any one of each group. Connection with the other rock-shafts is effected through cranks i^4 , affixed to all the rock-shafts, and a rod i^5 , connecting said cranks. A spring i^6 , acting against a pin on the rod i^5 , restores the rock-shafts and their cams and winds the cord on the drum when the lid is closed.

As an indicator to show the voter that he has depressed a push-piece to the proper extent I arrange a gong j in connection with the spindles which carry the push-pieces. A frame j' , pivoted to the sides of the box, extends along under the lower ends of all the spindles of one series, which project through the bottom of the support b . An arm of this frame extends under an arm of a pivoted striker j^3 , so that upon depression of any one of the spindles the gong will be struck. One gong is made to suffice for two series of spindles by the following arrangement: A second and larger frame k is pivoted to the sides of the box and extends under the spindles of

another series, and also extends under the striker j^3 , and upon depression of any one of the spindles of this other series the gong will be struck.

- 5 When the voting is to begin, the registering-wheels are all set at zero. The voting is done, as already made apparent, by depressing the push-pieces which stand opposite the names of the candidates to be voted for, and 10 a special implement is provided to accomplish the depression of the push-pieces, said implement being illustrated in Fig. 6. It comprises a handle n , in which is rotatively supported a spindle n' , ball-bearings n^2 being arranged in the handle, so that the spindle may turn readily. The upper end of each push-piece is preferably made with a conical socket o , and the end of the spindle is correspondingly tapered, as at o' , to engage said socket. 15 20 It will be seen that with this form of implement the part held in the hand does not turn, while the part engaging the push-piece may turn therewith.

When the voting has been completed, the 25 cover comprising the transparent plates and supporting-frame is removed, as are also the ballot-sheets, and the registering mechanisms are visible through the transparent plates which have been supporting the ballot-sheets 30 and the vote can be quickly counted and will be absolutely correct.

The numerous advantages possessed by a machine embodying my invention will be readily recognized. The machine is compact 35 and the parts are comparatively few, while at the same time the capacity is very large and a ticket of any size can be accommodated. The operation required of the voter is exceedingly simple and easily explainable to the 40 most ignorant. The implement used to depress the push-pieces will be connected by a chain or other suitable means with the box and will be always at hand. The voter is notified by the sounding of the gong when a 45 push-piece has been depressed to the required extent to register his vote, and hence there is no likelihood of a vote not being registered. Each vote is registered by positive mechanical means and absolute accuracy insured. 50 The ballot-sheets are thoroughly protected and rendered inaccessible, so that there is no possibility of their extraction or mutilation. At the same time they are completely visible. The vote being registered as taken insures 55 speedy returns. The returns are read without gaining access to the registering mechanism through the transparent ballot-supporting plates, and tampering with the mechanism cannot be accomplished without detection. 60 Absolute secrecy is established. The lid of the box, which conceals all the ballot-sheets and the mechanism, must be closed down after each voter has voted and raised again for the next voter, and in raising the lid all the parts 65 are restored to normal adjustment, so that it is impossible to tell how the preceding voter

voted. The operating implement adapted for insertion in the orifices containing the push-pieces enables said push-pieces to be compactly arranged, because they do not require 70 individual heads large enough to sustain the pressure of the operator's finger, the handle n and its spindle serving as a head for every push-piece.

In order to facilitate the setting of the registering-wheels at zero, each wheel is weighted at a point opposite the zero-mark, (see z , Fig. 2,) and the shaft f' , which supports the wheel, engages slots t in the frame, so as to be capable of sufficient movement to disengage the 80 wheels from the gears or worms and allow them to be rotated to their initial or zero position by the weights z , set-screws t' regulating the adjustment of the shaft.

When the machine is not in use, the registering-wheels are locked in their zero adjustment by means of rods m , inserted through registering openings in the wheels. These rods are withdrawn by the supervisor when the machine is to be put in use.

Having thus described my invention, what I claim as new, and desire to secure by Letters Patent, is—

1. In a voting machine, the combination of a suitably constructed inclosing casing having 95 provisions for supporting an elongated ballot sheet, registering wheels within the casing said wheels having a common axis which extends in the direction of longitudinal extent of the ballot-sheet support, and each wheel 100 being rotatively independent of all the others; and actuating pieces, one for each wheel, and arranged in line at one side of the ballot-sheet support so as to register with the names in the ballot-sheet.

2. In a voting machine, the combination of a suitable inclosing box or casing, registering-mechanism on suitable supports therein and having actuating means accessible at the top of the casing, and a transparent cover extending over the registering-mechanism and supporting a ballot-sheet adjacent to the actuating devices of the registering-mechanism, the latter being visible through the transparent cover when the ballot-sheet is removed.

3. In a voting machine, the combination of a suitable inclosing box or casing, registering-mechanism on suitable supports therein and having actuating means accessible at the top of the casing, a transparent cover held by the 120 supports of the registering-mechanism and carrying a ballot, and a transparent cover extending over the ballot.

4. In a voting machine, the combination of an inclosing box or casing having a number 125 of transversely-extending supports on the interior, registering-mechanism whose actuating devices extend through said supports at the top, transparent plates resting on said supports and confined laterally thereby, ballot-sheets on said plates, and a cover having 130 transparencies extending over the said bal-

lot-sheets between the transverse supports, said cover confining the ballot-supporting plates longitudinally.

5. In a voting machine, the combination with an inclosing box or casing having a transversely-extending interior support, of a plurality of registering-wheels loosely mounted on a common shaft and each rotatively independent of the others, and headless push-pieces operatively connected with said wheels respectively and extending through the transverse support, in which they are countersunk.

6. In a voting machine, the combination of a plurality of registering mechanisms, push-pieces operatively connected therewith respectively, a carriage having locking pieces for engagement with each push-piece when in its outermost or normal position, said carriage adapted to be moved to its locking position by an inward movement of any one of said push-pieces, and means for releasing the carriage, substantially as described.

7. In a voting machine, the combination of a plurality of registering wheels, spring-pressed push-pieces operatively connected therewith respectively and each having a driving shoulder and a locking shoulder, a spring-pressed carriage having spring-pressed pins projecting behind the driving shoulders of the push-pieces and adapted for engagement with the locking-shoulders thereof, and means for releasing the carriage from its locking adjustment.

8. In a voting machine, the combination of a plurality of registering-wheels, push-pieces operatively connected therewith respectively, a carriage having locking-pieces for engagement with each push-piece when in its outermost or normal position, said carriage adapted to be moved to its locking position by an inward movement of any one of said push-pieces, and means for releasing the carriage, which means control access to the ballot.

9. In a voting machine, the combination of a plurality of registering-wheels, spring-pressed push-pieces operatively connected therewith respectively and each having a driving-shoulder and a locking-shoulder, a spring-pressed carriage having spring-pressed pins projecting behind the driving-shoulders of the push-pieces and adapted for engagement with the locking-shoulders thereof, and means for releasing the carriage from its locking adjustment, which means control access to the ballot.

10. In a voting machine, the combination of a plurality of registering-wheels, spring-pressed push-pieces operatively connected therewith respectively and each having a driving-shoulder and a locking-shoulder, a spring-actuated longitudinally and laterally-movable carriage having spring-pressed pins projecting behind the driving-shoulders of the push-pieces and adapted for engagement with the locking-shoulders thereof under longitudinal movement of the carriage, and means for

moving the carriage laterally to disengage the pins from said locking-shoulders, said means controlling access to the ballot.

11. In a voting machine, the combination of a plurality of registering-wheels, spring-pressed push-pieces operatively connected therewith respectively and each having a driving-shoulder and a locking-shoulder, a spring-actuated longitudinally and laterally-movable carriage having spring-pressed pins projecting behind the driving-shoulders of the push-pieces and adapted for engagement with the locking-shoulders thereof under longitudinal movement of the carriage, a spindle carrying a cam to act on the carriage and move it laterally to release its pins from the locking-shoulders of the push-pieces, a drum on said spindle, and means for operating said drum, which means control access to the ballot.

12. In a voting machine, the combination with an inclosing box or casing having a hinged lid, of a plurality of registering-wheels within the box, push-pieces operatively connected therewith respectively and each having a driving-shoulder and a locking-shoulder, a spring-actuated longitudinally and laterally-movable carriage having spring-pressed locking-pins projecting behind the driving-shoulders of the push-pieces and adapted for engagement with the locking-shoulders thereof under longitudinal movement of the carriage, and suitable connections between the carriage and the box-lid whereby the raising of the lid moves the carriage laterally and releases its locking-pins from the shoulders of the push-pins.

13. In a voting machine, the combination with an inclosing box or casing having a hinged lid, of a plurality of registering-wheels within the box, push-pieces operatively connected therewith respectively and each having a driving-shoulder and a locking-shoulder, a spring-actuated longitudinally and laterally-movable carriage having spring-pressed locking-pins projecting behind the driving-shoulders of the push-pieces and adapted for engagement with the locking-shoulders thereof under longitudinal movement of the carriage, a spindle having a cam to act against the carriage and move it laterally, a drum on said spindle, and a flexible connection between the drum and the hinged box-lid.

14. In a voting machine, the combination of a registering-wheel, a spring-pressed longitudinally-movable and rotatable spindle having a spiral groove, a fixed pin engaging said groove, and a worm on the spindle and in gear with the registering-wheel, said worm being rotatively engaged with the spindle but held from longitudinal movement.

15. In a voting machine, the combination of two or more sets or rows of push-pieces longitudinally movable to operate on the registering mechanism, a bell, a pivoted striker, and bars extending across the rows of push-pieces respectively, and each having an arm engaging an arm of the striker.

16. A voting machine, comprising in its construction a series of countersunk push-pieces movable in orifices or guides in the casing of the machine, and a single independent pusher 5 insertible in and removable from either orifice for operating said push-pieces.

17. A voting machine comprising in its construction a series of countersunk push-pieces movable in orifices or guides in the casing of 10 the machine and socketed in their outer ends, and a single pusher having a tapering end for engagement with the sockets of the push-pieces and insertible in and removable from any one of the orifices, substantially as and 15 for the purpose described.

18. In a voting machine, the combination

with registering mechanism, and a rotatable and longitudinally movable push-piece for operating the same, with provisions for converting longitudinal into rotary movement 20 thereof; of a push-piece comprising a handle to be grasped by the operator, and a spindle rotatable in said handle and adapted to act on the push-piece, substantially as described.

In testimony whereof I have signed my 25 name to this specification, in the presence of two subscribing witnesses, this 20th day of November, A. D. 1893.

JOHN MCTAMMANY.
